UNITED STATES PATENT OFFICE.

EBEN E. WRIGHT, OF WATERTOWN, NEW YORK, ASSIGNOR TO WILDA M. WRIGHT, OF WATERTOWN, NEW YORK.

SHELF-WRAPPER.

No. 824,771.

Specification of Letters Patent.

Patented July 3, 1906.

Application filed December 19, 1904. Serial No. 237,405.

To all whom it may concern:

Be it known that I, EBEN E. WRIGHT, a citizen of the United States, residing at Watertown, in the county of Jefferson and State of New York, have invented certain new and useful Improvements in Shelf-Wrappers, of which the following is a specification.

This invention relates to improvements in shelf-wrappers, and has for its object the provision of a wrapper or carton to be used by dry-goods merchants and the like for the protection of all classes of fabrics and cloth goods from dust, soiling, fading, or shelf-wear.

15 A further object is to provide a shelf-wrapper which may be folded up or unfolded to receive or display fabrics and similar goods without waste of time or tedious labor and which may be fastened and unfastened in a 20 simple and ready manner.

Another object is to provide a shelf-wrapper which is capable of being enlarged or contracted, so as to facilitate the housing and protection of bolts or parcels of fabrics of different size, without requiring any alteration 25 of the wrapper itself.

The invention consists in features of construction hereinafter described and then sought to be clearly defined by the claim.

30 In the drawings forming a part of the specification, Figure 1 is a plan view of my improved shelf-wrapper, showing the form of the same when opened, also showing the overlapping edges of the cloth covering.

35 Fig. 2 is a view showing the wrapper partially folded. Fig. 3 is a view showing the wrapper completely folded, also the manner of applying and exemplifying the fastening means. Fig. 4 is a detail of the end flap or 40 wing, showing the manner of folding its edges or sides. Fig. 5 is an enlarged view of the metallic fastener.

Similar-reference-numerals are applied to corresponding parts throughout the figures 45 of the drawings, and in which—

2 represents the complete shelf-wrapper, which consists of the central body portion 3, the side wings or flaps 4 and 5, and the end flap 6, all of which are preferably formed 50 from a single piece of thin flexible paste-board, cardboard, or thick Manila paper. The external or exposed surface of the paper or board is covered or overlaid with a layer

of tough fabric, the surrounding edges 8 of which overlap slightly the inner surface of 55 the paper portion, as shown in Figs. 1, 2, and 4. The flaps 4, 5, and 6 all fold substantially on the dotted lines 7. The fabric covering or mounting is preferably pasted or glued to the paper or board in a secure manner.

9 represents a piece of cloth or fabric which is pasted to and covers the inner surface of the end flap or wing 6 as well as a portion of the main body portion 3, to which 65 it is also pasted. The flap or wing 6 is also provided with the foldable sides or wings 10, running lengthwise of the wrapper, and these are intended to fold inwardly on the dotted lines 10', and in order to facilitate their folding the slits 11 are made through the paper and outer cloth covering, extending from the outer edge on each side of flap 6 inwardly to the dotted lines 10'. The cloth lining or facing 9 is not slotted, and the portions of the 75 said lining which extend over the foldable sides 10 of flap 6 are unpasted or free, the object of the lining 9 being to form a sort of hinge for the flap 6, which is weakened somewhat at the point where it joins the 80 main body 3 by the slits 11, and at the same time by reason of the free edges 9' said lining 9 forms a guard to keep out dust, &c., when flap 6 is folded to the smaller size, as indicated by the dotted lines 10'. 85

In Fig. 3 and in the enlarged detail Fig. 5, 12 represents a metallic fastener or catch having a slotted opening 13, through which the attaching or securing strap 14 passes. This strap is then folded double, and its ends 90 are secured to the flap 4 of the wrapper by means of the rivet 15. More or less than two of the fasteners may be employed for the different-sized wrappers, and other suitable means of securing the same may be used. 95

In Figs. 1, 2, and 3, 16 represent the bindings traps or cords. These are secured to the back of the wrapper-body by means of the rivets 17 17. The straps or cords 16 are preferably made of flat strips of woven tape 100 or braid of a suitable length and strength to effect the tying or binding of the wrapper by drawing them tightly into the cleft 18 of the fasteners. The cleft or slit 18 is made narrow toward its inner point, so that when the 105 binding tape or cord 16 is drawn into it with

some force it will be held tightly and prevent the slipping or slackening of the tape, and thereby the opening or unfolding of the flaps 4, 5, and 6. By the use of the fastener 5 12 and the tape 16 the binding or tying of the wrapper into a close and compact package or parcel may be accomplished more quickly than by the methods formerly employed for the purpose, and the opening or 10 undoing of the wrapper may likewise be accomplished practically instantaneously by simply slipping the tape back out of the cleft 18. The projecting lug or portion 19 of the fastener is bent or turned upward 15 slightly at 20 for the purpose of guiding the tape 16 into the cleft 18. This provision enables the clerk or operator to effect the binding or tying of the wrapper without having to lift up the metallic plate 12. The slot or 20 hole 13 in the fastener is located in such position that when the tape 16 is drawn into cleft 18 the fastener lies or is held at right angles to wrapper, as shown in Fig. 3. The dotted line in Fig. 5 shows the direction 25 of the strain on the fastener when the cord or tape 16 is drawn taut. In Fig. 3, 21 represents a bolt of cloth or fabric inclosed in the wrapper.

When a bolt or roll of fabric has been reduced to a small size, the small wings or 30 flaps of wing 6 are folded inwardly, so that the package, wrapper and all, may be made more compact, so as to take up less room on a shelf. Two small bolts may be placed in

the one wrapper for the purpose of lessening 35 the number of packages.

One end of my improved shelf-wrapper is left open, so as to show at a glance the color or quality of the goods inclosed therein, the selvage edge of the fabrics always being 40 placed at the open end. I may prefer to provide a fourth flap to inclose the said open end.

It will be obvious to any one skilled in the art that various modifications may be made 45 in the invention that I have shown and described without departing from the spirit of the same, and I therefore do not restrict myself to the precise construction herein shown and described. 50

Having thus described my invention, what I claim, and desire to secure by Letters Patent, is—

A shelf-wrapper comprising a central body portion having folding flaps along the sides 55 thereof and an end folding flap, formed with inwardly-folding side wings, said end flap being provided with supplemental inwardly-folding wings which extend from the end flap to and upon the central body portion to 60 form a dust-guard, substantially as described.

In testimony whereof I affix my signature in presence of two witnesses.

EBEN E. WRIGHT.
